(57) **CLAIM**

The ornamental design for a magnetic suction wireless charger as shown and described.

DESCRIPTION

FIG. 1 is a perspective view of a magnetic suction wireless charger showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of detail "9" in FIG. 1; and,

FIG. 10 is another enlarged view of detail "10" in FIG. 1. The broken lines shown in the drawings are for the purpose of illustrating portions of the magnetic suction wireless charger and form no part of the claimed design.
